UNITED STATES PATENT OFFICE

WILLIAM H. LARAWAY, OF GRAND RAPIDS, MICHIGAN, ASSIGNOR OF ONE-HALF TO
LEONARD DE VOS, OF GRAND RAPIDS, MICHIGAN

VENDING MACHINE

Application filed November 18, 1929. Serial No. 407,914.

The present invention relates to vending machines and more particularly to improvements in the vending machine shown and described in my issued Patent No. 1,442,078, issued January 16, 1923, upon application by me filed on August 21, 1920.

The main objects of the invention are to provide improved means for preventing fraudulent manipulation of the machine; to provide an improved coin chute construction; to provide an improved vending block construction; to provide an improved tension block construction such as is hereinafter particularly described; and, to provide a vending machine having generally improved features over the device shown in my issued patent referred to above.

An illustrative embodiment of the invention is shown in the accompanying drawings, 20 in which:

Figure 1 is a fragmentary front elevational view, partly broken away to show the interior construction;

Figure 2 is a cross sectional view taken on line 2—2 of Figure 1;

Figure 3 is a cross sectional view taken on line 3—3 of Figure 2;

Figure 4 is an enlarged fragmentary cross sectional view of a portion of the device 30 showing certain novel features hereinafter more fully described; and

Figure 5 is a view taken along line 5—5 of Figure 2.

The vending machine shown in the drawings generally comprises a cabinet for the storage of articles to be dispensed. A spring tensioned lever, manually operated, causes a single article to be dispensed from the machine upon the reception of a coin.

Referring to the drawings, the cabinet generally comprises the top 1, the base 2, the sides 3, 4, the back 5 and the front panel 6.

A pair of vertically disposed members 7 form a partition 8 for the vertical storage of 45 a plurality of similar articles to be dispensed such as the battery of bottles 9. A horizontally disposed floor 10 is provided below the partition 8 to retain the articles in vertical storage and a vending block 11, provided with 50 a well 12 therein of substantially the same

shape as the article to be vended, is horizontally slidable on the floor 10 below the partitions 7. This well is normally in registration with the plurality of articles vertically retained thereabove and each alternate reciprocal movement of the vending block 11 on the floor 10 permits one of the articles to drop through the opening 13 to the curved chute 14 where it is delivered from the machine to the purchaser.

A tension block 15 for preventing reciprocal movement of the vending block 11 by fraudulent means as by tilting and jarring the machine, is retained between the cross member 16 and the vending block 11 by means of the coil expansion spring 17 within its well whose outer end bears against the U-shaped slidable member 18 which contacts the vending block 11.

A spring tensioned lever 19 pivotally mounted adjacent the side 4 of the cabinet is rigidly connected to a horizontally disposed rockable element 20 by means of the coupling 21. This rockable element is provided with a coin receiving well 22, and a plunger or trip 23 rigidly secured to the vending block 11, projects laterally therefrom partly into the coin receiving well.

A coin 24, inserted in the slot 25 travels through the vertical angularly disposed coin chute 26 into the coin receiving well 22 where it is held by the finger 30 projecting from its supporting member 31, and the flat inner surface of the coin bears against the head of the plunger 23 to push it rearwardly when the element 20 is rocked rearwardly by the manual operation of the lever. The plunger in moving rearwardly permits the coin to drop to the floor and causes the vending block to move rearwardly to thereby drop a single article from the well 12 through the opening 13 to the curved chute 14 for delivery to the purchaser. Rocking of the element 20 when no coin is in its well fails to vend an article since the head of the plunger is merely caused to pass through the slot 27.

A coiled contraction spring 28 secured at one end to the cabinet and at its other end to the rockable element 20 causes the element 20 to move forwardly upon releasing the

100

lever 19 and the plunger 23 is provided with an enlarged head and the forward movement of the element 20 pulling on the head of the plunger causes the vending block 11 to be 5 returned to its normal position to receive another article within its well 12. The provision of the vertical angularly disposed coin chute 26 prevents fraudulent manipulation of the machine by means of tools inserted 10 within the coin chute.

It will thus be seen that the improvements herein shown and described prevent fraudulent manipulation of the machine.

While but one specific embodiment of this 15 invention has been herein shown and described, it will be understood that numerous details of the construction shown may be altered or omitted without departing from the spirit of this invention as defined by the 20 following claim.

I claim:

A coin controlled vending machine including means for the vertical storage of a plurality of small articles to be dispensed, a 25 horizontal slideable vending block located below the said means and having a well for receiving a single article to be dispensed, friction means engaging the vending block and exerting a constant restraining action on 30 the same throughout the entire movement thereof, an oscillatory coin carrying member having a coin receiving passage, a stop spaced from the vending block and arranged to limit outward movement of the coin carrying member 35 and provided with a pin extending into the said coin passage for supporting a coin when the said coin carrying member is at the limit of its outward movement, and means arranged to be engaged by the said coin for 40 actuating the vending block.

In testimony whereof I have hereunto set my hand at Grand Rapids, Michigan, this 14th day of November, 1929.

WILLIAM H. LARAWAY.
